UNITED STATES PATENT OFFICE.

CLARA B. O'CONNOR, OF NEW YORK, N. Y.

GAME APPARATUS.

1,211,748.

Specification of Letters Patent.

Patented Jan. 9, 1917.

Application filed June 27, 1916. Serial No. 106,232.

To all whom it may concern:

Be it known that I, CLARA B. O'CONNOR, a citizen of the United States, residing at New York city, in the borough of Manhattan and State of New York, have invented certain new and useful Improvement in Game Apparatus, of which the following is a specification.

This invention pertains to game apparatus, designed to impart certain information through the playing of the game, thereby combining instruction with amusement and causing such instruction to be received as an incident to the play, without special thought or effort.

The apparatus may be used in a variety of ways or to play a number of games, and the character and extent of the information may be varied at will.

20 Briefly stated, the apparatus comprises a game board divided into equal sections advisably of contrasting ground or color, each section in turn subdivided into squares or other relatively small spaces of uniform outer line and dimensions, said smaller spaces bearing designs, legends, or both, of character to convey the information to be impressed upon the minds of the players; and a set of markers, cards or "pieces", each bearing a 25 design, legend, or like matter corresponding with that of one or another of the smaller subdivisions of the board, with or without additional matter. The markers of each 30 main division of the board advisably have a color or ground corresponding with the field 35 of the main section to which they respectively belong, or are otherwise identified therewith.

The two main divisions of the board are 40 separated by two or more rows of the smaller subdivisions, which may be devoid of designs or legends, this intermediate space constituting a battle ground or field on which the preliminary moves of the game are made, 45 and permitting a shifting of the markers or pieces in the opening of the play. All the subdivisions except those of the middle field or maneuvering space are utilized, and bear 50 designs or legends or both, and there is one marker for each space so provided. In playing the game the markers corresponding to the spaces of each half or section of the board are placed upon squares of the other half or section thereof, and the object is to 55 move the respective pieces to the spaces bearing like designs or legends. The character

and extent of movement will be governed by rule, and may be varied to provide a variety of games.

The dimensions of the board, the number 60 of subdivisions, and the character of the designs and legends may be varied indefinitely. In practice I find it convenient to divide the board into forty-eight equal squares, eight in one direction and six in the other, 65 the two proximate rows of six on opposite sides of the medial line forming the field or preliminary maneuvering space; but as indicated these details are variable at will. All 70 the spaces or subdivisions except those of the field are to bear designs, legends, or both, and are to be used in playing the game.

In the accompanying drawings: Figure 1 is a plan view of the board; and Fig. 2 is a view showing one of the markers to be used 75 therewith.

By way of illustration merely, I have taken as a basis of the game notable points of scenic beauty and interest east and west of the Mississippi River, which is assumed to 80 flow through the medial field or maneuvering space, while the eastern and western sections are bounded by the Atlantic and Pacific Oceans respectively. Each subdivision or space of the three outermost rows of each 85 section will bear suitable picture or sketch, or data, or both, giving information concerning the designated place. In the western division, for instance, the Petrified Forest of Arizona; the Yellowstone National Park, 90 Wyoming; the Sequoia National Park, California; the Rocky Mountain National Park, Colorado; the Grand Canyon, Arizona; Great Salt Lake, Utah; the Yosemite National Park, California; Casa Grande Ruin, 95 Arizona; Mt. Rainier National Park, Washington, may be noted as examples. Similarly, in the eastern division, the Thousand Islands in the St. Lawrence River; Niagara Falls, New York; Gettysburg battlefield, 100 Pennsylvania; Luray Caverns and Natural Bridge, Virginia; Watkins Glen, New York; Mammoth Cave, Kentucky; Harpers Ferry, West Virginia; Mt. Desert, Maine, and the like, readily suggest themselves as suitable 105 for the purpose stated.

Referring again to the drawing, A indicates the board as a whole, which may be divided at its midlength into two sections hinged to fold together, as is common with 110 game boards.

B indicates the intermediate field or ma-

neuvering space, and C and D the remaining sections, here represented as the eastern and western divisions. The several sections B, C and D are divided into squares or regular spaces *a*, *b* and *c*. The intermediate section field, or maneuvering space B comprises the innermost pair, indicated by *c*, of the eight transverse rows of squares *a* and *b* into which the board is shown divided, the number of 10 rows and the number of divisions or spaces to a row being, however, variable as desired. The spaces *c* of the intermediate field or maneuvering section are preferably left entirely blank. The spaces *a* and *b*, however, 15 bear the designs, data, or both, before referred to. Thus in the eastern section the space devoted to Niagara Falls may contain a sketch of the falls with the words "Niagara Falls, New York", and such other data or 20 information concerning the same as may be desired. Similarly, in the western section a space devoted to the Yosemite National Park may contain a picture or sketch of some particular point of interest in the park, together 25 with the words "Yosemite National Park, Cal.", and any further data desired. It is of course to be understood that the illustration, data, or both, may be varied indefinitely, and may even be graded in successive 30 boards to suit players of different ages.

For each square or subdivision *a* and *b* of both sections C and D there is a marker, piece, or "man", E, of corresponding ground or color and bearing the same picture, legend or data, or any of them, preferably a facsimile of the matter placed upon the square or section of the board. The markers are preferably of circular form as shown in Fig. 2, and of a diameter to avoid overlapping a given space *a* or *b*, as is usual with game boards and markers of this character. In the present instance this has the further advantage of permitting the color or ground of the section in which the marker may at 45 any time be, to be seen, while the legend, design, or other matter of said spaces *a* and *b* is wholly or practically hidden from view by the marker, as indicated by the dotted circle in Fig. 1.

When the game is to be played the markers corresponding to the eastern division are given to the player at the opposite or western division, and those of the western division to the player holding the eastern division. The play begins by a forward movement of a piece, thereby uncovering a square or space of the division from which the move is made. Movements may be made only to squares or sections unoccupied, and 55 to which access may be had without passing over another marker.

The rules of the game may be varied greatly, either confining the movements to one space forward, laterally or backward, 60 or permitting a continuous movement in

varying directions so long as an open pathway is afforded by succeeding vacant spaces. The object of the players is so to move their respective pieces or markers as first to cover the entire field of the opposing player, the 70 movements being in accordance with whatever specific rules are adopted for a game, and the one first covering his opponent's field being deemed the winner.

By providing several sets of rules as many 75 different games may be played on the same board and with the same markers. The game may be further varied by playing certain of the games with the markers initially turned face downward, so that in making 80 the first move or a given number of moves the player will be in ignorance as to whether he is approaching or moving away from the ultimate "home" or stopping place of a marker.

The theory of the game is that constant or frequent sight of given objects and reading of short legends or data, fix in the mind of the observer or reader the appearance of such objects and the data concerning them. 90 The information is impressed upon the mind without effort and almost unconsciously, but is so firmly pictured in a short time that the image or the facts will be retained indefinitely. The game apparatus hence affords a pleasing way of imparting useful 95 information, and fixing it in the minds of the players, as scarce any other method of teaching or instruction will do. While primarily designed to impart general knowledge or information, the range or field of instruction or of the particular topics or lines of information to be imparted, is practically limitless.

I am aware that various game boards divided into sections and bearing figures or designs, legends or data, and the like, have heretofore been proposed, but so far as I am aware no one has hitherto devised a game board designed to impart and fix in the 110 minds of the players, definite and useful information after the manner here proposed. Nor am I aware of any prior instance in which the entire field of each player is utilized to receive or contain the information to 115 be imparted, or in which each square or space of the respective player's fields is provided with a special and distinctive design, legend or data, or both, and with a marker corresponding thereto.

Having thus described my invention, what I claim is:—

1. A game apparatus comprising a board divided into three sections, each section in turn subdivided into similar smaller spaces, 125 said smaller spaces of the two outermost divisions or sections bearing respectively pictures, legends, or data suitable to impart to the players desired information; and a series of markers, one for each subdivision 130

of the two outer sections, said markers respectively bearing matter identifying them with the different subdivisions, and being of dimensions practically to cover the matter appearing on any given subdivision.

2. A game apparatus comprising a board having a mid-section and two outer sections of distinctively different color or ground separated thereby, the several sections subdivided 10 into uniform smaller spaces, each subdivision of the outer sections bearing pic-

tures, legends, or like means of imparting information; and a series of markers equal in number to the subdivisions of said outer sections, of dimensions practically to cover the matter of said subdivisions, of color or ground to correspond therewith, and respectively bearing matter corresponding with that of the several subdivisions.

In testimony whereof I have signed my name to this specification.

CLARA B. O'CONNOR.
